CLAIM

The ornamental design for a coffee capsule, as shown and described.

DESCRIPTION

FIG. 1 is a top perspective view of a coffee capsule according to my new design.

FIG. 2 is a top plan view thereof; and,

FIG. 3 is a side elevation view thereof.

The broken lines in FIG. 2 depict portions of the coffee capsule in which the design is embodied that are not considered part of the claimed design.

1 Claim, 3 Drawing Sheets*FIG. 1*

FIG. 2

FIG. 3
